UNITED STATES PATENT OFFICE.

SMILIE TILTON, OF ALTON, NEW HAMPSHIRE.

IMPROVED EXTENSION-TABLE.

Specification forming part of Letters Patent No. **101,545**, dated April 5, 1870.

To all whom it may concern:

Be it known that I, SMILIE TILTON, of Alton, in the county of Belknap and State of New Hampshire, have invented an Improved Extension-Table; and I do hereby declare that the following is a full and exact description thereof, reference being had to the accompanying drawings, making part of this specification—

Figure 1 being a view of the under side of the improved table when closed and folded into its most compact form; Fig. 2, a view of the under side thereof, when the folding leaves are raised, but without extension-boards; Fig. 3, a view of the under side of the same extended; Fig. 4, a central longitudinal vertical section of the table, as in Fig. 2; Fig. 5, a transverse vertical section of the same; Fig. 6, an end view of the table, the end legs being detached; Fig. 7, a view of the inner side of the end legs and connecting-rail; Fig. 8, an edge view of one of the central leaves of the table.

Like letters designate corresponding parts in all of the figures.

First, in order to make the table as compactly portable as possible, the end legs, A A, connected by the end rail *a*, are provided with fastening-sockets *b b*, and the ends of the side rails B B are provided with fastening-heads *c c* to fit into the sockets in the manner of some bedstead-fastenings, whereby the legs can be readily separated from the rails for the purpose of transportation, and again quickly attached. This feature is to be considered as an element of the general construction of the table, with a view to the purposes aimed at in this invention. The central leg, C, is secured to a cross-bar, *e*, which is attached to the side rails by screws or otherwise, so as to be detachable.

Second, the permanent boards D D of the table-top have a turning movement around a central pivot or disk, *f*, of the frame to the extent of ninety degrees, so that they may either be lengthwise of the frame, as in Fig. 1, or crosswise, as in Fig. 2; and to their outer edges, respectively, leaves E E are hinged. The width of the two boards D D is equal to that of the frame, so that when they are lengthwise of the frame the leaves can be turned down, as in Fig. 1, but when they are turned crosswise the leaves will be supported by the

frame, as in Fig. 2. Thus the table can be put into a shape so as to occupy but little room when not in use, and then quickly be put into a form for use. The central pivot or disk, *f*, has its socket one-half in one and the other half in the other board, D, so that the two boards can be readily separated for inserting extension-boards G G G.

Third, the table is extended when the boards D D and the leaves E E are crosswise of the frame, and the frame is extended by the usual means of sliding lap-rails B B, but with tightening-screws *g g*; and, in addition to this means of extension, in order to give the table a capability of unusual extension, with the greatest compactness when closed together, there are hinged fly-rails H H, to give extension to the slide-rails B B, as in Fig. 3, but to be turned in and rest adjacent to the end rails when not in use, as shown in Figs. 1 and 2. The length of these fly-rails, to secure their perfect operation, is only one-half of the width of the space between the slide-rails, so that they will not overlap each other when folded in. They might be allowed to turn farther in against the sliding rails; but they are made to fold against the end rails in order that they may be moved automatically in shortening the table and not require to be handled. To effect this movement there are inwardly-curved guide rods or bars *h h* secured to and projecting from the sliding rails inside of the same, substantially as shown in Fig. 3, and pins *i i* projecting downward from the movable ends of the fly-rails. These pins strike the guide-rods as the frame is closing, and swing the said fly-rails far enough inward to be brought around automatically into the required position when the end rails strike them.

There are also leaf-supports *l l* on the two end rails *a a*, to sustain the leaves E E.

Thus I have three means of extension: first, for a single extension-board, or two, by simply drawing out the leaf-supports; second, by the sliding side rails B B; third, by the hinged fly-rails H H; and all of these may be employed together to lengthen the table to its fullest extent, as indicated in Fig. 3.

The permanent top boards D D are held upon the frame by means of semicircular cleats *m m*, in a central position at the inner edges on the under sides thereof. First, each cleat

has a lip or rim, *n*, which fits into grooves *p p* in the inner side of the side rails *B B*; and, second, it has a lip, *o*, around its semicircular socket, to fit around the disk or pivot-head *f*. The latter keeps the boards in place while turning them around the central pivot, and the former keeps them in place when the boards are arranged across the frame of the table and in extending.

The extension-boards *G G G* are held in place by means of similar lips sliding in the rail-grooves, or by dowel-pins and holes, in the usual manner.

What I claim as my invention, and desire to secure by Letters Patent, is—

1. The arrangement for turning movement of the permanent boards *D D* of the table, with the leaves *E E* hinged upon the same, as and for the purposes herein specified.

2. The hinged fly-rails *H H*, in combination with the sliding rails *B B*, as and for the purpose herein set forth.

3. The curved guide-rods *h h*, in combination with the fly-rails *H H*, provided with the pins *i i*, for the purpose specified.

4. The cleats *m m*, with their lips *n* and *o*, in combination with the central pivot, *f*, and grooves *p p* in the sliding rails *B B*, as specified.

5. In combination with the turning boards *D D* and their leaves *E E*, and with the sliding extension-rails *B B* and fly-rails *H H*, the detachable end legs *A A*, for the purpose specified.

Specification signed by me October 27, 1869.

SMILIE TILTON.
